DESIGN FOR A COMBINED HANDBAG AND SPECTACLE HOLDER

Ann Rose Schiff, Columbus, Ohio

Application August 27, 1948, Serial No. 148,341

Term of patent 14 years
(Cl. D87—3)To all whom it may concern:

Be it known that I, Ann Rose Schiff, a citizen of the United States of America, residing at 1445 Broad Street, Columbus 15, Ohio, have invented a new, original, and ornamental Design for a Combined Handbag and Spectacle Holder, of which the following is a specification, reference being had to the accompanying drawing, forming a part thereof, wherein:

Fig. 1 is a perspective view of a combined handbag and spectacle holder illustrating my new design;

Fig. 2, a rear perspective on a slightly reduced scale of the combined handbag and spectacle holder, illustrating the handbag in opened position; and,

Fig. 3, a front perspective on a further reduced scale of the combined handbag and spectacle holder, illustrating the flap of the duplicate spectacle holder which is disposed within the handbag, in open position.

I claim:

The ornamental design for a combined handbag and spectacle holder, substantially as shown and described.

ANN ROSE SCHIFF.
